UNITED STATES PATENT OFFICE

165,731

COMBINED TELEVISION AND RADIO- PHONOGRAPH CABINET

Samuel E. Adler, Chicago, Ill.

Application January 6, 1951, Serial No. 13,694

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Combined Television and Radio-Phonograph Cabinet, of which the following is a specification, reference being had to the accompanying drawings, forming part thereof.

Fig. 1 is a front elevational view of a combined television and radio-phonograph cabinet, showing my new design, the doors thereof being closed;

Fig. 2 is an elevational view of the left side of the cabinet;

Fig. 3 is a perspective view thereof, the doors being open; and

Fig. 4 is a fragmentary sectional view on line 4—4 of Fig. 1.

The dominant features of my design reside in the portions shown in full lines of the drawing.

The right side of the cabinet resembles the left side and the back is plain.

I claim:

The ornamental design for a combined television and radio-phonograph cabinet, as shown and described.

SAMUEL E. ADLER.
